UNITED STATES PATENT OFFICE.

EBERHARD SCHNEIDER, OF NEW YORK, N. Y.

PROJECTING APPARATUS.

985,068.

Specification of Letters Patent. Patented Feb. 21, 1911.

Application filed January 16, 1907. Serial No. 352,534.

To all whom it may concern:

Be it known that I, EBERHARD SCHNEIDER, a citizen of the United States, residing in the city, county, and State of New York, have invented a new and useful Improvement in Projecting Apparatus, of which the following is a specification.

This invention relates to projecting apparatus, and more especially to projecting apparatus adapted for use in connection with both moving-picture exhibiting apparatus and ordinary fixed slides showing objects at rest.

The invention contemplates the provision of an improved stand on which both moving picture apparatus and fixed slides may be suitably supported for the purposes of exhibition, an improved lamp-house and supporting device therefor which is readily shiftable so that a single lamp may be used for both the exhibition of moving pictures and the projection of fixed slides, and an improved lens support whereby the accurate positioning of projected pictures on a field may be insured without altering the position of the stand bearing the projecting apparatus.

The invention also contemplates other minor improvements which will appear in the course of the following description, in which reference is had to the accompanying drawings, wherein corresponding parts are designated by similar characters of reference throughout.

In the drawings: Figure 1 is a general view in side elevation of the stand, lamp-house, lens supports, and slide holders of a projecting apparatus embodying the present invention, the moving-picture exhibiting apparatus being omitted for the sake of clearness. Fig. 2 is a view in rear elevation of the lamp-house and adjacent structures. Fig. 3 is a top plan view of the structures shown in Fig. 1, with the exception of the legs or pillars for the stand. Fig. 4 is a transverse vertical section through the lamp-house on the line 4-4 of Fig. 5. Fig. 5 is a view of the lamp-house partly in longitudinal median section and partly in side elevation. Figs. 6 and 7 are detail views showing the mode of connecting the legs with the bed of the stand. Fig. 8 is a detail view showing the ball-and-socket adjustment of the lens support.

In describing the apparatus, I will first describe the stand, as the other parts of the apparatus are all supported thereby, and will then proceed with the description of the other structures forming parts of the invention.

The stand consists of a bed 1 which is preferably an aluminum casting longitudinally slotted as shown at 2 and provided with a stiffening web 3 on its under side. The stiffening web is made in skeleton form, as shown in Fig. 1, and at the ends openings 4 are formed for the passage of clamping bolts 5 by which the legs are secured. The surface of the web adjacent to each of the openings 4 is flat, but each leg 6 is provided at its upper end with a disk 7 serrated near its periphery on the inner face so as to obtain firm hold upon a washer of leather or other suitable material 8 which is interposed between each leg and the web 3. The legs 6 are preferably of tubular form and composed of a plurality of telescoping sections, as shown in Fig. 1, and the clamping bolt 5 for each pair of legs is preferably provided with a wing nut 9 to facilitate the clamping and releasing of the legs. To limit the angular adjustment of the legs and prevent the possibility of collapse of the stand in case the legs are set in nearly horizontal position, a notch 10 is formed in the lower margin of the web adjacent to each of the bolt holes 4 and a stud 11 on the inner face of each disk 7 lies in the notch when the legs are clamped in place and limits the angular movement of the leg by contact with one end of the notch. At the rear of the bed 1 a lateral extension 12 is provided, as best shown in Fig. 3, and upon this lateral extension is clamped a bracket 13 presenting at the top a pair of ears 14 which afford support for a transverse rod 15 and having at the bottom an inclined bead or rib 16 which forms a sort of guide or track which operates with the rod 15 to form a guide or track for the lamp-house.

The lamp-house is designated generally by 17 and is supported by a pair of ears 18, through which the rod 15 extends, and a roller 19 engaging the inclined bead or rib 16 and mounted in a small bracket 20 provided at the base of the lamp-house frame. These supporting devices for the lamp-house permit lateral movement of the lamp-house

along the rod 15 and also permit the lamp-house to be tilted forward about the rod 15 as a center and brought over upon the bead of the stand when the brackets for supporting the lenses and slide holders are removed.

The details of construction of the lamp-house are best shown in Figs. 1, 4 and 5. It is constructed principally of sheet metal, but the sheet metal parts are preferably 10 mounted on a frame 21 of cast aluminum, of which the bracket 20 forms an integral part. At the front the lamp-house is provided with the usual thimble 22 to form a lens support, and just behind this thimble within 15 the lamp-house is provided a sliding shutter 23 which works in vertical guides 24 at the sides of the lamp-house. This shutter is provided to cut off the heat of the lamp and protect the lens when a picture is not 20 on the screen, and the shutter-operating devices are of such character that the shutter can be easily and quickly controlled by the operator without introducing his hand within the lamp-house. An arm 25 rigidly 25 mounted on a shaft 26 extending longitudinally of the lamp-house near the top and at one side is connected with the shutter by means of a link 27 pivotally attached to the free end of the arm 25. The shaft 26 is 30 rocked by means of an arm 29 mounted at the rear end of the shaft and disposed in a recess formed in the exterior of the lamp-house to receive it. The shaft 26 is provided at its forward end with a collar 30, 35 and a coiled spring 31 disposed between the collar 30 and the front wall of the lamp-house, serves to draw the shaft forward so as to insure the engagement of a lug 32 on the head of the arm 29 in engagement with 40 the rear wall of the lamp-house. This lug 32 is of wedge shape and is adapted to enter a notch 33, in the wall of the lamp-house when the shutter is raised and the arm 29 is turned into substantially horizontal position. 45 To close the shutter it is necessary for the operator merely to release the lug from the notch by giving the arm 29 a slight upward swing, after which the weight of the 50 shutter will be sufficient to cause it to descend to the position shown in Fig. 4, turning the shaft 26 as it descends and swinging the arm 29 into vertical position.

The lamp-house is provided with a door 55 34 in the right side wall to afford ready access to the upper portion of the interior and a rear door 35 affords convenient access to the base of the lamp-house. Both doors are provided with suitable latches to keep them 60 closed and a central opening 36 in the door 34 enables the operator to observe the condition of the lamp without opening the door. The base of the lamp-house is preferably 65 curved as shown in the drawings and a sliding bracket 37 for supporting a portion of

the lamp is mounted on a rod 38 extending longitudinally of the lamp-house along one side at the top of the curved base. This bracket is prevented from tilting by a curved arm which conforms approximately 70 to the curvature of the base and has its free end extended laterally, as shown at 40, to rest on a ledge formed therefor. Adjustment of the bracket is effected by an arm 41 extending through a slot in the lamp-house 75 frame, thus enabling the operator to shift the position of the bracket without inserting his hand within the lamp-house.

To afford a draft through the lamp-house so as to remove products of combustion and obtain the cleaning effect due to the passage 80 of a current of air, an opening is formed in the top of the lamp-house and a plate 42 having segmental side wings 43 secured thereto is pivoted at the forward end of the opening. These side wings engage the sides of the opening and coöperate with the plate 42 to form a device by which the vent at the top may be varied in size. The plate 42 and the side wings 43 also serve to form a 85 sort of flue by which the current or draft through the top of the lamp-house is given a rearward as well as upward direction. The supply of air to create the draft is admitted at the base of the lamp-house 90 through a perforated plate 44 forming the lower section of the front wall of the lamp-house and the air so admitted is directed upwardly immediately behind the front wall by a baffle plate 45. The object of this arrangement is to concentrate the draft of air 95 as nearly as possible at the front of the lamp-house where it will have a cooling effect upon the front wall and upon the lens L mounted in the thimble 22, thereby affording a certain amount of protection to the lens from the heat developed by the lamp used for projection.

Mounted on the bed 1 of the stand and adjustable thereon, I have shown a pivoted 100 double bracket 45 upon which are supported a slide holder 46 and a water cell 47, the latter being set to the side on which the moving picture apparatus is mounted when in use, so as to afford the inflammable celluloid film bearing the moving pictures a certain amount of protection from the heat of the projecting lamp. Both the slide holder and the water cell are preferably provided 105 with shields of the usual type to cut off extraneous light and also to concentrate the light from the projecting lamp upon the field on which the pictures are displayed. Another adjustable bracket 48 is also mounted 110 on the bed of the stand and this bracket 115 carries an improved lens holder especially adapted to facilitate the positioning of the picture projected from a slide held in the slide holder 46. Mounted on the bracket 120 48 is a supplemental bracket 49 having a verti- 125

cal arm which turns in the bracket 48 and a horizontal arm on which is mounted a sliding collar 50 provided with a set screw. The sliding collar 50 has a laterally projecting arm 51 to which a correspondingly shaped plate is secured by means of a clamping screw 52. Between the arm 51 and the plate 52 is gripped a ball 53, the arm 51 and the plate 52 being excavated to form a 10 socket to receive the ball. The ball 53 carries a lens-supporting ring 54 into which a lens 55 is threaded or otherwise fastened. The ball-and-socket joint formed by the arm 51, the corresponding plate, and the ball 53 afford means whereby the position of the lens 55 may be very accurately adjusted to insure the focusing of the light projected through a slide in the holder 56 on exactly the same field as the light projected through 20 the water cell 47 and suitable moving picture exhibiting apparatus mounted in front of the water cell.

In the use of the improved apparatus above described, the customary procedure 25 is to mount moving picture exhibiting apparatus on the bed of the stand in such position that light from the lamp will fall on the moving picture film after passing through the water cell, and the moving pictures will then be projected on a suitable screen. When the moving picture apparatus is in use the lamp-house occupies the position shown in Fig. 3 immediately behind the water cell. After the exhibition, 30 of the moving pictures contained on one reel of film, it is customary to throw on the screen a picture from an ordinary slide showing objects at rest, and for this purpose a slide holder 46 is provided. By following the exhibition of moving pictures with a picture from a slide, the attention of the audience is kept during the interval required to remove from the moving picture apparatus the film which has been exhibited and 40 to introduce another film. In order to make it possible to project a picture from a slide on the screen during a change of films and without the use of an additional complete projecting apparatus, the lamp-house is made 45 shiftable laterally in the manner already described. Accordingly, when it is desired to change the moving picture films and to project a picture from a fixed slide, the lamp-house is shifted from the position 50 shown in Fig. 3 to a position just back of the slide holder 46, the lamp-house being readily slidable on the rod 15 and the rib, or bead 16 on the bracket 13. After the 55 change of film to the moving picture apparatus has been effected, the lamp-house is restored to its normal position behind the water cell and the moving picture apparatus again set in operation.

In setting up the apparatus above described for operation, one pair of the legs 6

is so adjusted in length as to bring the bed 1 to the proper height with the legs standing at a slight incline, approximately as shown, the bed 1 is then set horizontally or at the inclination necessary to properly center a 70 picture on the screen, and finally the other pair of legs is then brought into position to engage the floor or other structure on which the stand rests, and are secured in this position. The lamp-house is first set behind the 75 water cell and light is projected through it and the moving picture apparatus to insure the proper location of the moving pictures on the screen. The proper positioning of the 80 moving pictures having been assured, the lamp-house is shifted to the left and light thrown through the slide holder and the lens 55. If the light so projected is not properly distributed on the screen so that the picture presented by the slide in the holder occupies 85 the same field as the moving pictures, the lens 55 is quickly and accurately adjusted by means of the ball-and-socket joint upon which it is supported, and then the parts are securely clamped to prevent disarrangement. 90

Having thus described my invention, what I claim as new and desire to secure by Letters Patent is:

1. In apparatus of the character specified, the combination with a lamp-house of lamp-house supporting devices upon which said lamp-house is laterally movable, the supporting devices comprising a rod, members at the front of the lamp-house through which said rod passes, and a guide below 95 said rod against which the lower portion of the front of the lamp-house presses.

2. In apparatus of the character specified, the combination with a lamp-house of supporting devices upon which said lamp-house is slidably and tiltably mounted; said supporting devices comprising a round rod, lugs at the front of said lamp-house through which said rod passes, a guide-way below 100 said rod, and a roller at the front of said 105 lamp-house which rests against said guide.

3. In projecting apparatus, the combination with a stand having a bed upon which projecting lenses may be removably mounted of a lamp-house tiltably mounted on said 110 stand adapted to be tilted over upon said bed when not in use.

4. In projecting apparatus, the combination with a stand having a longitudinally slotted bed, of a lamp-house mounted at one 115 end of said bed and lens brackets adjustably and removably secured in said slots.

5. In projecting apparatus, a lamp-house having a chamber provided at the forward end with a projection aperture, a shutter 125 slidably mounted in said chamber on the forward wall and adapted to close said chamber, and shutter-operating devices comprising a shaft extending longitudinally of said chamber, a slotted arm fixed on said 130

shaft adjacent to said shutter, a stud on said shutter engaging the slot in said arm, an operating arm or lever fixed on said shaft external to said chamber, and a spring catch mechanism associated with said shaft and adapted to operate when said shutter is moved to uncover the projection aperture and to hold said shutter in such position.

C. In projecting apparatus, a lamp-house having an escape opening in the top for products of combustion and provided in its forward end with a projection aperture, said lamp-house having air inlet openings formed in the lower portion of the front wall and a baffle plate within said chamber and adjacent to said inlet openings, whereby air admitted to said chamber is caused to rise along the inner surface of said forward wall and exert a cooling effect upon a lens mount.

ed in or adjacent to said projection aperture. 20

7. In projecting apparatus, a lamp-house provided near its base with a longitudinally disposed guide rod and a lamp bracket slidably mounted on said guide rod and having 25 an arm projecting laterally through the wall of said lamp-house and having another arm extending across the base of the lamp-house and engaging the side of the lamp-house opposite the guide rod, whereby said bracket 30 is supported without interference with its movement along said guide rod.

In testimony whereof, I have signed my name in the presence of two witnesses.

EBERHARD SCHNEIDER.
